UNITED STATES PATENT OFFICE.

WILLIAM F. WALDA, OF FORT WAYNE, INDIANA, ASSIGNOR TO DEISTER CONCENTRATOR COMPANY, A CORPORATION OF INDIANA.

ORE-CONCENTRATOR.

1,321,577.

Specification of Letters Patent. Patented Nov. 11, 1919.

Application filed January 24, 1917. Serial No. 144,151.

To all whom it may concern:

Be it known that I, WILLIAM F. WALDA, a citizen of the United States of America, and resident of Fort Wayne, in the county 5 of Allen and State of Indiana, have invented certain new and useful Improvements in Ore-Concentrators, of which the following is a specification.

This invention relates to improvements 10 in ore concentrators of the reciprocating table type, and pertains particularly to construction for supporting the table proper in reciprocable position. The object of the improvement is to so support the deck that it 15 may be moved freely in its reciprocal action while being supported and at the same time be free from influences that tend to augment inherent detrimental vibrations that sometimes develop when the deck is reciprocated 20 rapidly. Another object is to provide means for maintaining, constantly, lubrication of the supporting bearings.

The above objects are accomplished by the construction illustrated in the accompanying drawings, in which:—

Figure 1 is a perspective view of the under construction of a concentrator showing the bearing pockets in connection therewith;

Fig. 2 is a plan view of the underside 30 of the reciprocating deck and showing also the arrangement of feet that are secured thereto;

Fig. 3 is a transverse sectional view of the concentrator at a point adjacent the 35 head end thereof;

Fig. 4 is a side elevation of the machine shown partly in longitudinal section;

Fig. 5 is a vertical section of one of the 40 bearing pockets and the corresponding foot in bearing relation therewith;

Fig. 6 is a bottom plan view of one of the feet; and

Fig. 7 is a plan view of one of the bearing pockets.

Similar characters of reference indicate corresponding parts throughout the various views and referring now to the same:

The illustrations show the adaptation of the present invention to a concentrator of 50 known construction and which is disclosed in Letters Patent of the United States No. 1,026,764 issued to Gustave A. Overstrom on May 21, 1912, which construction is herein presented as an example to disclose the use of 55 the invention. The invention however, may

be readily adapted to concentrators and other machinery differing from that herein shown. In the present instance the tilting frame (1) of the machine has arranged thereon a series of box-like pockets (2), each of 60 which has a central elevating bearing (3). These are arranged in substantially a common plane and move bodily with the tilting frame (1). The upper surface of the bearing (3) is flat and the metal of which 65 the block is made is preferably hardened in order to resist wear. The boxes (2) are coupled together in opposite pairs by corresponding pipes (4), the ends of the pipe entering the boxes at a point above the level 70 of the bearing surfaces of the blocks (3) therein, the purpose of the pipes being to convey the liquid lubricant from one pocket to the opposite one. Also, one of each pair of pockets has a feed-pipe (5) connected 75 therewith through which lubricant is received. Secured to the under side of the reciprocating deck (6) are numerous castings (7) having pendant feet (8), that are positioned to rest respectively upon the 80 blocks (3) correspondingly. In the face of each foot are made oil-grooves (9) to facilitate movement of lubricant to the contacting surfaces of the foot and block. The castings (7) are supported in their connection with the deck by laterally arranged angle irons (10) which serve to hold the castings fixedly in position.

The contacting surfaces of the feet and bearing blocks are approximately of equal 90 area, and the weight of the reciprocating deck is borne by the bearing blocks with the feet resting thereupon, the bearing surfaces of the blocks and feet being smooth and submerged in the lubricant (11) that is supplied to the pockets admit of the movement of the deck in any direction parallel to the plane of the bearing surfaces.

The deck (6) is also provided with pull-bearings (12) and (13) respectively at its 100 opposite ends which are acted upon oppositely by the spring-puller (14) at the one end and the driving-head (15) at the other. The action of the spring-puller and driving-head effects the reciprocation of the deck 105 and holds the latter in longitudinal tension and also in alinement upon its bearings which consist of the feet and bearing blocks.

As the table is reciprocated upon its bearings in the direction applied thereto by the 110

driving-head and spring-puller, the feet slide upon the bearing blocks and support the deck. While it is the intention to reciprocate the deck in longitudinal direction only, the contacting surfaces of the feet and bearing blocks are made flat throughout their bearing surfaces so as to admit of free movement of the deck upon its bearings as it is driven and also as it may vibrate more or less laterally. Such inherent lateral trembling movements of the deck as may occur are unrestricted by the supporting bearings composed of the blocks and feet, as their contacting surfaces admit of free movement of the deck in all directions in a plane parallel to that of the contacting surfaces. Thus, re-actionary vibrations of the deck, such as vertical trembling, do not develop and the efficacy of the concentrating action of the machine is thereby enhanced inasmuch as vertical trembling of the deck disturbs settlement of mineral values thereon.

The method of applying reciprocal movement to the deck by means of the spring-puller at one end thereof and the driving-head at the opposite end, contributes to the smoothness and directness of action of the deck upon the bearings. The draft of the puller and driving-head being opposite, the deck is held in tension and directly in alignment with the intended direction of reciprocal movement, and the freedom of the deck to be moved by the actuating mechanism afforded by its supporting bearings, obviates re-actionary vibrations that cause detrimental disturbances of the mineral values during transit on the surface of the deck.

What I claim is:—

1. In bearings for supporting reciprocable concentrating tables and the like, a series of pendant feet rigidly attached to the table, and each having a flat bearing face at its bottom; and a corresponding series of pockets suitably mounted, and each having an upwardly projecting block therein with a flat upper face extending in a plane beneath the top of the pocket and adapted to admit of movement of the corresponding foot bearing thereon in any direction parallel with the face thereof.

Copies of this patent may be obtained for five cents each, by addressing the "Commissioner of Patents, Washington, D. C."

2. In bearings for supporting reciprocable concentrating tables and the like, a multiplicity of pendant feet rigidly attached to the table; a corresponding series of pockets suitably mounted, each having therein an elevated flat bearing face extending in a plane beneath the top of the pocket and adapted to afford bearing support for the corresponding foot and admit of sliding movements thereof in all directions parallel with the face thereof, each pocket being adapted to contain lubricant to a level above the bearing face therein; and means for conveying lubricant to said pockets.

3. In bearings for supporting reciprocable concentrating tables and the like, a multiplicity of suitably mounted pockets, each having therein an upwardly projecting block with a flat upper face, there being a space within the pocket extending entirely around the block therein, said flat face lying in a plane lower than the top of the pocket; and a corresponding multiplicity of pendant feet rigidly fixed to the table and respectively projecting into the pockets and resting upon the blocks therein correspondingly.

4. A bearing for supporting a reciprocable member, a casting with a box-like pocket suitably mounted and having a central upwardly projecting block therein with a flat upper face, there being a space within the pocket extending entirely around the block, said pocket being adapted to hold lubricant to a level above said face; and a casting fixed to the reciprocable member having a flange extending downwardly over the top of the pocket upon the exterior thereof, and a central pendant foot having a flat face at its bottom adapted to rest upon the corresponding bearing face of the block, said castings being so formed as to admit reciprocating movements of the foot upon the block in all directions parallel with said faces.

In testimony whereof I affix my signature, in presence of two witnesses.

WILLIAM F. WALDA.
